UNITED STATES PATENT OFFICE.

FRANZ LÖSEL, OF BRUNN, CZECHOSLOVAKIA.

METHOD OF AND MEANS FOR CONTROLLING THE WATER CIRCULATION IN WATER-TUBE BOILERS.

Application filed June 5, 1924. Serial No. 718,034.

To all whom it may concern:

Be it known that I, FRANZ LÖSEL, a citizen of Czechoslovakia, residing at Brunn, Czechoslovakia, have invented certain new and useful Improvements in the Methods of and Means for Controlling the Water Circulation in Water-Tube Boilers, of which the following is a specification.

In water tube boilers the speed of the circulation of the water in the water tubes may be controlled by the number and arrangement of the tubes, further by the path of the fire gases and more particularly by the inclination of the water tubes, but as is well known, this is possible only within comparatively narrow limits. For this reason it has already been proposed to control the circulation of the water by movable vanes or the like provided within the boiler. But in these attempts it has never been taken into account that the different temperatures in the various parts of the tubes of the boiler require different and controllable speeds of the water in order that the temperatures and speeds of the water may be in the proper relation.

According to the present invention different and variable speeds of the water are positively produced in the various water tube regions by mechanical water moving means located outside, such impressed speeds corresponding to the different temperatures in the water tube regions. Such mechanical water moving means preferably consist of a pump having a plurality of pressure degrees, the successive pressure degrees being connected with the successive water tube regions.

The annexed drawing illustrates by way of example and diagrammatically an embodiment of my invention.

The top drum K is connected by a pipe *a* to the intake of a pump P having a plurality, say three, pressure degrees or cylinders 1, 2, 3. The water tubes W of the boiler are divided into three groups, each constituting a region, by partitions *b* dividing the water chambers into three compartments *c*₁, *c*₂, *c*₃ which are connected to the cylinders 1, 2, 3 by pipes *d*₁, *d*₂, *d*₃ in such a manner that the lowermost group *w*₃ of water tubes most exposed to the fire gases is connected with the last cylinder 3 with the highest degree of pressure, from which the water escapes with the greatest

speed. The next group *w*₂ of water tubes is connected by the pipe *d*₂ with the medium pressure cylinder 2 and the uppermost group *w*₁ of water tubes is connected with the cylinder 1 of the lowest pressure. Thus 60 the water is forced to flow through the various regions or groups of water tubes with different speeds.

In order to permit the speed of the water in the various groups or regions to be controlled in accordance with the temperature of the fire gases I provide in some suitable part of the furnace a thermometric apparatus E of any known or preferred construction which through the medium of a 65 speed controlling apparatus F of any known or preferable construction increases or reduces the speed of the pump P and thereby controls the speed of the water in the pipes *d*₁, *d*₂, *d*₃ and in corresponding water tubes 70 W of the boiler in accordance with the temperature of the fire gases in the furnace of the boiler. 75

It is evident that the temperature of the fire gases decreases during the flow thereof 80 through the different tube regions W. The different temperatures and the temperature changes in the different regions of the boiler tubes are therefore during operation more or less dependent on and defined by the 85 temperature in a suitable part of the furnace where the thermometric device may be provided, because as a result of the increase of the temperature of the fire gases in such part of the furnace the temperature of the 90 fire gases in the different boiler tube regions *w*₁, *w*₂, *w*₃ increases or tends to increase, and as a result of the decrease of the temperature of the fire gases in such part of the fire gas 95 flow the temperature in the different boiler tube regions decreases or tends to decrease.

As a result of the control by the thermometric apparatus E increase of the fire gas temperatures causes the water velocities in the different tube regions *w*₁, *w*₂, and *w*₃ 100 to be increased, and decrease of the fire gas temperatures causes the water velocities in such different tube regions to be decreased. Such changes in water velocities occur in accordance with changes of temperature in 105 the different regions of the boiler tubes *w*₃, *w*₂ and *w*₁.

It is evident that thermometric means E may be positioned in any suitable or desirable part of the furnace or the fire gas 110

flow therein. For example, such means E may be placed between or behind the boiler tubes. It is also evident that such thermometric means could be positioned either in 5 suitable or desirable parts or regions of the boiler tubes, the simplest arrangement being that in which the thermometric means is located entirely in a suitable part of the furnace.

10 The invention offers the advantage that owing to the circulation of water at different speeds in different regions, positively produced by external means, any unequal expansions of the various regions by heat 15 are avoided in the regular operation of the boiler as well as in steaming up. Such unequal expansions would occur if the water circulation were uniform in all regions of the boiler tubes or were caused by the temperatures of the water alone.

20 What I claim is:

1. The method of controlling the water circulation in water tube boilers consisting in supplying water and in positively producing 25 in various separate regions of the water tubes unequal and variable speeds of water which correspond to the different temperatures existing in the said regions.

2. In combination with a water tube boiler 30 mechanical means for imparting motion to water, comprising an intake connected with a water space of the boiler, a plurality of escape openings connected with different regions of the water tubes of 35 the boiler, and means for causing water drawn through said intake to pass through the different escape openings at different speeds to cause different velocities in different regions of the water tubes of the boiler 40 in accordance with the different temperatures in said regions connected to different regions of the water tubes of the boiler in which the temperatures are different, to cause corresponding different water velocities 45 in the tubes of said different regions.

3. In combination with a water tube boiler 50 a pump for imparting motion to water, such pump comprising an intake connected to a water space of the boiler and a plurality of escape openings at points of different pressures connected to different regions of the water tubes of the boiler, in which the temperatures are different, to cause corresponding different water velocities 55 in the tubes of said different regions, and means for operating the pump.

4. In combination with a water tube boiler 60 a pump adapted to increase the pressure of water successively to a plurality of degrees, such pump comprising an intake connected to a water space of the boiler and a plurality of escape openings at different pressure points for water under different degrees of pressure, means for connecting such openings to different regions of the

water tubes, in which the temperatures are different, to cause corresponding different water velocities in the tubes of said different regions, and means for controlling the pump.

5. In combination with a water tube boiler having the water tubes thereof divided into groups, a pump comprising a plurality of stages adapted to increase the pressure of water successively to different degrees of pressure, such pump comprising an intake connected to a water space of the boiler and escape openings for the individual stages, such escape openings being connected each to one of said groups of water tubes, in which the temperatures are different, to cause corresponding different water velocities in the tubes of said different groups, and means for operating the pump.

6. In combination with a water tube boiler or a pump for imparting motion to water, such pump comprising an intake connected to a water space of the boiler and a plurality of escape openings at different pressure points connected to different regions of the water tubes of the boiler, in which the temperatures are different to cause different water velocities in the tubes of said different regions, a driving gear for operating the pump and means responding to the temperature of a heating medium for controlling the speed of said pump.

7. The method of controlling the water circulation in water tube boilers consisting in supplying water and in forcing the water through various separate regions of the water tubes at different pressures to produce unequal and variable speeds of water to correspond to the different temperatures existing in said regions.

8. The method of controlling the water circulation in water tube boilers consisting in taking water from a part of the boiler and in increasing the pressure of the water in stages and forcing the water at the pressures of said stages through various separate regions of the water tubes to produce unequal and variable speeds of water to correspond with the different temperatures existing in said regions.

9. The method of controlling the water circulation in water tube boilers consisting in supplying water and in forcing the water through various separate regions of the water tubes, in which the temperatures are different, with velocities corresponding with the different temperatures and in controlling the water velocities through the different regions of the water tubes in accordance with the temperature of the fire gases in a suitable part of the furnace.

10. The method of controlling the water circulation in water tube boilers consisting in taking water from a part of the boiler, in increasing the pressure of the water in

stages, in forcing the water at the pressures corresponding to said different stages through various separate regions of the water tubes, in which the temperatures are different, to cause different water velocities corresponding to the different temperatures in said regions and in controlling the pressure stages and the water velocities through the water tubes in accordance with the temperature of the fire gases.

11. A steam generator comprising water tubes divided into separate groups, and means including a pump having intake and discharge ports connected with said steam generator, for forcing water from a part of the generator with different pressure degrees and velocities through various groups of water tubes to correspond with different temperatures which exist in the various groups.

12. A steam generator comprising water tubes divided into groups which are separated from each other at their water entrance portions, and means including a pump having intake and outlet ports connected with said steam generator, for forcing water from a part of the generator with different pressure degrees and velocities through said various groups of water tubes to correspond with different temperatures which exist in the various groups.

13. A steam generator comprising water tubes divided into groups which are separated from each other at their water entrance portions, a pump having different pressure stages, an intake connection leading from the boiler to said pump, and connections leading from different pressure stages of said pump to said separated water tube groups for directing water of different pressure degrees to pass therethrough at different velocities to correspond with different temperatures which exist in the various groups.

14. A steam generator comprising water

tubes divided into groups which are separated from each other at their water entrance portions, a pump having different pressure stages, an intake connection leading from the boiler to said pump, and connections leading from said pump to said separated water tube groups for forcing water of different pressure degrees at different velocities therethrough, the higher pressure stage of said pump being connected with the water tube group situated in a combustion space of highest temperature and the lower pressure stages with the water tube groups situated in the furnace spaces with corresponding lower temperatures.

15. A steam generator comprising water tubes divided into groups which are separated from each other at their water entrance portions, means for forcing water from a part of the boiler with different pressure degrees and velocities through said various groups of water tubes to correspond with different temperatures which exist in the various groups, and regulating means for controlling the pressure degrees of such water forcing means and the water velocities through said water tube groups.

16. A steam generator comprising water tubes divided into groups which are separated from each other at their water entrance portions, means for forcing water from a part of the boiler with different pressure degrees and velocities through said various groups of water tubes to correspond with different temperatures which exist in the various groups, and means, including a thermometric device, for controlling the pressure degrees of the water forcing means and the water velocities through the water tube groups in accordance with the temperature of the fire gases.

In testimony whereof I affix my signature.

FRANZ LÖSEL.
